UNITED STATES PATENT OFFICE.

ROLAND CECIL ADAMS, OF WESTCLIFF-ON-SEA, ENGLAND.

DEVICE FOR FORMING THE METALLIC FASTENING BANDS OF CAP CLOSURES.

Application filed February 25, 1928, Serial No. 257,034, and in Great Britain February 18, 1927.

This invention relates to machines for use in the manufacture of cap closures for bottles or other containers and more particularly in the manufacture of that kind of such closures which comprise a closure element adapted to cover the mouth of such container and a retaining element for holding said closure element in situ, said retaining element consisting of a metallic band 5 strip bent into a ring with its two ends fastened together by means of a tongue and slot connection and adapted to be applied around the neck of the container.

The primary object of the invention is 15 the provision of a machine for automatically forming the metallic band strip into the ring and the invention consists broadly in the combination of a core device, means for feeding said strip around said core device 20 so that the two ends overlap and means for increasing the effective circumference of said core device in such a way as to cause the tongue and slot connection for said two ends to interlock thereby forming an endless 25 band.

In order that the invention may be the more clearly understood a machine in accordance therewith will now be described reference being made to the accompanying 30 drawings wherein:—

Figures 1, 2, 3 and 4 show in end elevation certain of the essential parts of the machine illustrating position of the parts during their progressive stages of operation.

Figure 5 is a plan of certain of the parts shown in Figures 1 to 4 together with another part shown in disassembled relation.

Fig. 5^a is a fragmentary view showing a 40 grooved roller and a bifurcated projection for cooperating with the metal strip prior to its being shaped.

Figure 6 is a side elevation of the machine.

Figure 7 is a plan view.

Fig. 7^a is a view of the gear wheel having teeth on its face toothed on less than one-half its circumference.

Figure 8 is an end elevation.

Figure 9 is a view to an enlarged scale of the strip as blanked out, and

Figure 10 is a perspective view of the formed band.

Thus the machine is adapted to form the 55 bands of cap closures of the character described in prior application No. 223,768

filed October 3rd, 1927. These bands as blanked out take the form shown in Figure 9; that is to say they take the form of each of a flat strip having tongues stamped out adjacent the respective ends, each tongue having its root or its connected end nearest to, and its extremity furthest from the adjacent end and the ends of the two tongues being slightly bent to opposite 60 sides of said strip.

The operation of forming said bands consists of engaging each tongue in the hole formed by the stamping out of the other tongue and then inwardly flanging one edge 70 of the band as shown in Figure 10.

Describing first the function of the machine with reference to Figures 1 to 5, the machine comprises a rotatable member *a* of generally cylindrical formation having 75 one end thereof formed so as to provide a projection *a*¹. This projection, as shown, is in the form of a short cylinder coaxial with, and of slightly less radius than, the main portion of said member *a*, and having 80 a "bite" or recess which extends throughout the whole of its axial length, and with edges parallel to one another from one circumferential periphery nearly to the other. This "bite" has slidably mounted therein, 85 in splined relation to the parallel edges, a member *a*² which is so shaped externally that in its outermost position (as shown in Figures 1 and 4) it completes the circumferential periphery of the part *a*¹. The 90 main portion of the member *a* has an axial opening *a*³ formed therein at the end from which said part *a*¹ projects, and the inside edge of the member *a*² also has a "bite" 95 out of it which has its sides parallel to the sides of the former "bite" and about the same distance apart as the diameter of said hole *a*³ and has its end approximately semi-circular as shown and with a bevelled edge *a*⁴. Said member *a*² is held to its inner position by means of springs *a*⁵.

The projection *a*¹ is closely surrounded by a shallow circular wall *b* having two interruptions in which are located respective rollers *c* and *d* which have their axes 105 parallel to the axis of said member *a* and are biased inwardly by springs *d*⁴ towards said member to limited positions such that said rollers normally bear against the circumferential periphery of said projection 110 *a*¹ and move inwardly only a small distance further when permitted to do so by the posi-

tion of the member a^2 . These rollers are carried at the extremities of respective levers c^1 and d^1 and are movable by virtue of the movement of said levers about their 5 axes.

Coaxial with the axis of said member a is an axially reciprocable die e (shown only in Figure 5) in axially disassembled relation). This die has centrally a cylinder 10 e^1 , a plain annular surface e^2 at right angles to the axis of reciprocation, a bevelled or slightly conical surface e^3 which extends from said surface e^2 , an outer convexo conical surface e^4 and an outer convexo cylindrical surface e^5 extending rearwardly from said surface e^4 and of a diameter equal to the maximum diameter of said surface e^4 . The projection e^1 has a more or less cone shaped end and is of such a diameter as to be adapted 15 to fit into the axial hole a^3 of the member a . The surface e^3 is of a diameter equal to or just greater than that of the inner surface of the wall b . The surface e^4 is of such a minimum and maximum diameter 20 as to be adapted, as the die moves inwardly towards the member a to engage corresponding chamfered surfaces c^2 and d^2 on the levers c^1 and d^1 in such a way as to cause the rollers c and d to be moved outwardly 25 away from the axis of the member a . As said die moves further inwardly the inner surfaces c^3 and d^3 of said levers are adapted 30 to slide on the cylindrical surface e^5 of said die, whereby the rollers c and d are held 35 quite clear of the part a^1 .

The member a is adapted to rotate intermittently in a counter clockwise direction 40 synchronously with the reciprocation of the die e , the arrangement being such that said member a makes a complete revolution and then pauses for a period equal to, or greater than, the period of revolution. The member a when at rest is on the opposite side of the 45 die from the roller c . This position is shown in Figures 1, 2 and 4. When the period of rest commences the die is making its inward or operative stroke and will have moved a sufficient distance on the 50 surfaces c^3 and d^3 to be sliding on the convex cylindrical surface e^5 whereby the rollers c and d are held clear of the part a^1 .

A chute f is provided along which the unformed strips s are fed in succession. Said chute is so directed that said strips are 55 adapted to be fed between said roller c and a coacting member a^2 past the angle or point x . Said strips are adapted to be fed with their square ends forwards and with the tongues adjacent said square ends directed away from 60 the part a^1 and towards said roller c as shown in Fig. 2.

Starting at the extreme instroke of the die, at this position the last band has just been 65 formed and closely circumscribes the part a^1 . Said formed band will be ejected, as said

die moves to its outer position, by means which will be described hereinafter. The following band (whose formation is about to be described) has been fed down the chute by feeding mechanism which will also be 70 hereinafter described until further movement is prevented by its forward end abutting against the surface e^5 of the die. The member a is at its period of rest, so that the hindermost point x is opposite the roller 75 c . The surfaces c^3 and d^3 are resting on the surface e^5 so that the rollers c and d are clear of the part a^1 . This position is shown in Figure 1, the preceding band and the die 80 e not however being shown.

When the die e has moved outwardly during a small part of its stroke the surface e^5 clears the end of the strip s and the roller c being still clear of the part a^1 , said strip is fed by the feeding mechanism between said roller c and the aforesaid corner x until its forward end abuts against the edge of the "bite" opposite to said aforesaid corner x . As said strip is fed in this way the preceding 85 formed band is being ejected and the ejection is timed so that said formed band will just miss fouling said strip. Approximately simultaneously with the arrival of the strip at this position the surface e^4 disengages the surfaces c^3 and d^3 and the rollers c and d 90 close upon the part a^1 , the former roller of course holding the strip s firmly against the aforesaid corner x . This is the position shown in Figure 2.

Immediately after this, the period of rotation of the member a commences and the strip is carried round with the part a^1 . When said member a has nearly completed its revolution; that is to say about when the foremost of the corners x arrives at the roller c the rear end of the strip is drawn clear of the chute and said strip completely encircles the part a with the tongues opposite the "bite" as shown. When said foremost corner x passes said roller c the latter moves 105 a small distance into the "bite" to its limited position thereby ensuring that the two ends overlap as shown in Fig. 3 so that each tongue lies inside the other. This is the 110 position shown in Figure 3.

Immediately after this position is arrived at the rollers c , d are lifted clear of the part a^1 by the returning die and this may or may not permit the strip to spring 115 to a greater circumference so that the tongues interlock. In any case the strip now completely encircling the part a^1 will continue to rotate therewith until the member a arrives at its position of rest. The tongues will then be opposite the "bite" on 120 the one side and the fixed wall b on the other.

Just after said member a arrives at the 125 position of rest the cone shaped end of the forward projection e^1 engages with the

chamfered surface a^1 of the semi-circular end of the "bite" in the inner edge of the member a^2 , and, as said projection continues to move inwards said member a^2 is slid radially in the bite of the part a^1 until it finally reaches its outermost position hereinbefore referred to in which its outermost edge completes the circumferential periphery of the part a^1 . By this action first the circumference of the strip s is increased until the tongues are forced into engagement with one another and next said interengaged tongues are squeezed between the outer edge of the member a^2 and the adjacent wall b and are thereby flattened against the band so that the connection is rendered semi-permanent. The band is thus secured in its ring form. Simultaneously with or immediately after this action the surface e^2 abuts against the outer edge of the strip and, the surface e^3 surrounding said edge closely, said edge is constrained to bend inwardly as required. By the time the die arrives at the inner end of its stroke this inward bending is completed to the required extent and the formation of the band is complete. This position is illustrated in Figure 4. The die then commences to move outwardly until the entire movement thereof is completed. It will be noted that the member a^2 rapidly recedes to its inner position so that the following strip is not delayed in moving to its position against the foremost point α .

The ejection of the formed band during the outstroke of the die is adapted to be effected by means of three ejector rods h which reciprocate as one unit in holes formed through the member a parallel to the axis thereof and near to the circumferential periphery of the part a^1 . The extremities of these rods emerge from the surface of said part a^1 shortly after the die has commenced its out stroke and continue to emerge until just before said die has reached the outer end of its stroke. At this moment they are withdrawn suddenly. During the emergence the extremities of said rods engage the in-turned lip of the band as will be seen from Figure 4 and force said band off the part a^1 . During the withdrawal the band falls clear of said rods into a suitable container. The sudden nature of said withdrawal is in order to ensure that the band shall have fallen clear before it can possibly foul the die during its return stroke for forming the succeeding band.

To ensure the retention of the strip in situ whilst it is being carried round with the part a , a member g is provided located outside the circle formed by the band and having an overhanging lip g^1 which, when said member g is in its normal position, retains the band against axial movement. The member g however is movable more or less radially away from the axis of the member

a so that the lip g^1 clears the band, and said member is adapted to be so moved by virtue of the engagement of the surface e^4 of the die with a chamfered cam surface g^2 on said member g . The arrangement is such that said lip g^1 clears the band just before the die commences its forming operation and does not return to its normal position until said band has been moved sufficiently far by means of the rods h to prevent its outer edge being stopped by said lip g^1 .

Associated with the chute f are two feed rollers f^1 and f^2 . The roller f^1 is mounted underneath the floor of the chute and has its circumferential periphery just projecting through an opening in said floor. The roller f^2 is supported above the floor of said chute by means of an oscillating bracket f^3 comprising projections f^4 and f^5 . The bracket f^3 oscillates between two positions and the arrangement is such that at one of said positions the roller f^2 is pressed into engagement with the roller f^1 , and the projection f^4 just touches said floor of said chute, whilst the projection f^5 is lifted clear of the said floor. At the other of said positions the roller f^2 and the projection f^4 are lifted clear and the projection f^5 engages said floor of said chute. The roller f^2 is permanently in rotation in such a direction as to tend to feed the strip along the chute towards the part a^1 .

When the bracket f^3 is in the former position a strip is adapted to be fed into the chute. This strip slides down the chute until it abuts against the projection f^4 and remains there until said bracket f^3 moves to its latter position. Said strip then slides further until it abuts against the projection f^5 where it stops until said bracket returns to its former position. Thereupon said projection f^5 is lifted and said strip is gripped between the rollers f^2 and f^1 , the projection f^4 only resting lightly on its surface, so that it is fed forward until after interruption by the surface e^5 at the position of Figure 1 it assumes the aforesaid position of Figure 2. The strip stops at this position until the member a commences rotating whereupon as aforescribed the strip is drawn around the part a^1 by the co-operation of said part a^1 and the roller c . This last operation is effected whilst the bracket is still at its said former position and thus the rearmost tongue has to be drawn past the projection f^4 and between the rollers f^1 and f^2 . In order that this may be possible said projection f^4 is bifurcated and the roller f^2 , towards which said tongue is turned, is grooved.

After this occurs, the following strip may be inserted into the chute where it is stopped either by the projection f^4 if it is inserted immediately as the tail end of the preceding strip is seen to disappear or by the projec-

tion f^5 if the insertion is delayed until the bracket has moved to its latter position. At whatever moment the insertion is effected however the co-operation of the two projections will prevent the possibility of two strips fouling, provided only such insertion is not effected until the tail of the preceding strip is seen to disappear.

From the above the timing of the rocking 10 of the bracket will have been deduced. Thus the change from the latter position to the former position is made just before the die is at the inner end of its stroke so that said strip abuts against the surface e^5 of the 15 punch, as hereinbefore described, ready to complete its forward movement to the position of Figure 2 when permitted to do so by the withdrawal of said surface e^5 . The change from the former position to the latter 20 position takes place just after the rear end of the strip has been drawn past the projection f^5 .

Describing now with reference to Figures 25 6, 7 and 8 the general construction of the apparatus the parts are all supported by means of a massive base structure 1 the form of which will be apparent from the drawing. On this base at one end is mounted a horizontal main power driven shaft 2.

30 The member a is mounted coaxially on the extremity of a horizontal actuating shaft 3 which is located at right angles to said shaft 2. This actuating shaft 3 carries a bevel gear 5 which engages a bevel gear 35 6 carried by the main shaft 2. The teeth of the bevel gear 6 are cut away to extend only slightly more than half of its circumference and the gear ratio is such that the teeth during their engagement with the gear 5 will cause the latter to make exactly one revolution. In this way the member a is 40 caused to make intermittent revolutions alternating with periods of rest as hereinbefore described.

45 The die e is mounted upon a cross member 7 by means of a bolt 8 screw threaded at both ends and a nut 10. Said bolt passes through said cross member as shown and the die is screwed on to the inner end thereof 50 of with a spacing collar 9 between said die and said cross member. The nut 10 is screwed onto the rear end of the bolt thereby securing the die in place.

Said cross member is mounted on the base 55 1 by means of two guide pins 11 rigidly secured to said cross member and longitudinally slidable in holes 12 in said base. Said cross member is adapted to be reciprocated by means of eccentrics 13 on the main shaft 60 2 the straps of said eccentrics being secured to said member by means of rods 14 and screws 15. In this way the reciprocation of the die is effected. The feed rollers c and d are maintained in permanent rotation and 65 these feed rollers are each carried by a

shaft, such as 16, shown in Fig. 7, having a bearing 17 and each bearing 17 is intended to be mounted to rock about a transverse axis in a stationary bearing 18. This structure is well known in machines of this art 70 and further detail description is believed to be unnecessary. The rocking bearings 17 enable the levers c^1 and d^1 to oscillate as described. As shown by Fig. 7, the shafts 16 carry gear wheels 19 which are driven by 75 means of a gear wheel 20 which is rigidly secured to the bevel wheel 5. The levers c^1 and d^1 are pivoted at 21 direct to the base 1 as shown.

The ejection pins h which reciprocate in 80 holes in the member a as stated are mounted upon a collar 22 which slides axially upon the shaft 3. Said collar 22 is adapted to be reciprocated by means of another collar 23 against which it abuts, which collar 23 is in turn reciprocated by the lower end of 85 a lever 24 the upper end of which is pivoted about a shaft 25. Said lower end of the lever 24 is bifurcated so as to engage the flanges of a circumferential groove formed 90 in said collar 23 as shown in Fig. 6. Said lever 24 is oscillated by means of a cam 26 engaging with a complementary cam surface on said lever, the two cam surfaces being formed as shown in Figure 6 so that said 95 lever pushes said collar 23 to the left slowly and then permits it to return to the right quickly. This return of the two collars and the lever is effected by means of springs 27 coiled about the rods h . It will thus be seen that the rods h emerge from the part a^1 for ejection of the formed band and return quickly to avoid the band fouling 100 the die as hereinbefore stated.

The said member g is carried as shown at 105 one end of a lever 28 which is oscillatable about the aforesaid shaft 21. Said member g is slotted at 29 and is held against the casting of the base 1 by means of a screw 30 passing through said slot. In this way 110 said member is permitted to reciprocate as described. Said member is biased to its normal or down position by means of a leaf spring 31.

The bracket f^2 is oscillatable about the 115 axis 32. The upper end of said bracket is bifurcated and in the slot of bifurcation is located a rod 33 which is oscillatable about a vertical pivot 34. A cam engaging 120 surface is formed on this rod which surface is engaged by a complementary cam surface formed on the face of a cam wheel 35 mounted on a driven shaft 36. Upon rotation of said shaft 36 the cam surfaces between the wheel 35 and the rod 33 cooperates 125 so as to oscillate said rod about its pivot 34 and thereby oscillate said bracket f^2 about its axis 32. In this way the projections f^4 and f^6 are caused to function as hereinbefore described.

The feed roller f^2 has rigidly and coaxially associated therewith a gear wheel 37 and this gear wheel is in engagement with a gear wheel 38 mounted on a shaft 39 the 5 other end of which carries a gear wheel 40. Said gear wheel 40 engages a gear wheel 41 mounted on a shaft 42 which carries a bevel wheel 43 which engages with another bevel wheel 44 mounted on the aforesaid shaft 10 36. It will thus be apparent that a step up transmission train is established from said shaft 36 to said feed roller f^2 .

When the teeth on the bevel wheel 6 leave the teeth on the bevel wheel 5, there is a tendency for said latter wheel to continue running under its own momentum. In order to overcome this tendency a pawl 45 is provided pivoted upon a pivot 46, which pawl at the moment said teeth disengage, is pulled 20 into engagement with the teeth of said bevel wheel 5. This pawl carries a projection 47, as shown in Fig. 7, which rests on a cam 48 which is rigid with the bevel wheel 6.

Said pawl 45 is moved into engagement

with the teeth of the wheel 5 by means of 25 a spring 49 and the cam 48 on shaft 2 is so formed that such engagement is permitted throughout the whole period of disengagement of the two bevel wheels 5 and 6. Said pawl 45 slides in the slot of a bifurcated 30 support 50.

What I claim and desire to secure by Letters Patent is:—

A machine for forming a sheet metal strip having a tongue at each end into a 35 retaining ring having on one longitudinal edge a flange, said machine comprising a rotatable member, with means associated with said member for feeding a flat strip toward said member and to bring the two 40 ends of the strip into engagement, said rotatable member having associated therewith a member movable relative thereto for increasing its circumference and to effect an 45 interlocking of the ends of the strip to form a continuous endless band.

In witness whereof I affix my signature.
ROLAND CECIL ADAMS.
